BALING PRESS DOOR STRUCTURE

Alexander S. Mackenzie, Houston, Tex., assignor
to Anderson, Clayton & Company, Houston,
Tex., a joint-stock association of Texas

Application July 22, 1932, Serial No. 624,085

22 Claims. (Cl. 100—19)

The present invention relates to baling press door structures.

The upper baling chambers of baling presses of the type used for baling cotton are usually provided with side doors and end doors, which doors are hinged either at their side edges or their bottom edges. Some form of locking means must be provided to hold the doors in baling position, which locking means must be released after the bale has been compressed and while a tremendous pressure is being exerted against the doors by the compressed material. Various arrangements of cams or eccentrics have been used to control the locking means with each of these prior art devices. A great number of the locking arrangements used with press doors are released by moving the doors slightly inwardly against the already highly compressed material and this naturally adds to the difficulty of releasing the locking means, as well as increasing the tendency of the doors to suddenly move to open position once the locking means is released. The fact that the press doors are usually hinged at one edge thereof is also a disadvantage in that when it is desired to relieve the pressure of the doors against the bale, the door must be swung wide open to accomplish this result because of the fact that the pressure cannot be relieved over the portion of the door adjacent the hinge without entirely swinging the door away from the compressed material.

Briefly described, the apparatus of the present invention includes hinged doors, which doors may be moved rectilinearly with respect to their hinges so that the pressure existing within the compressed material may be uniformly relieved without swinging the doors to entirely open position. The doors are provided at their free ends, i. e., the ends opposite the ends at which the hinges are positioned, with locking means. My invention includes means to release the locking means from locked position without the necessity of moving the doors inwardly against the compressed material and which means will permit the locking means to be gradually and smoothly released and without the occurrence of any sudden shock.

It will be understood from the above that the principal object of the present invention is to provide a door structure for baling presses whereby the doors may be readily released from baling position and which will counteract the tendency of the material within the baling chamber to suddenly expand at the moment when the doors are released.

Another object of the invention is to provide a door structure for baling presses by which the doors may be given a slight preliminary opening movement before they are moved to fully opened position, this preliminary movement of some of

the doors being in a rectilinear direction and the preliminary movement of all of the doors being limited by positive means so that the doors are entirely under the control of the operator and cannot move suddenly to fully open position.

A further object of the invention is to provide a door structure wherein the preliminary opening movement of the doors will simultaneously cause them to be unlocked.

Referring to the drawings wherein like numerals indicate like parts throughout the several views,

Figure 1 is a side elevation of the press structure with parts broken away;

Figure 2 is a horizontal sectional view taken on the line 2—2 of Figure 1, with parts broken away, and showing one upper baling chamber and a portion of the other upper baling chamber;

Figure 3 is a side view of the structure shown in Figure 2, viewed in the direction of the arrow 20 "X" of Figure 2;

Figure 4 is an end view showing the left-hand end of the press shown in Figure 1;

Figure 5 is a fragmentary vertical sectional view taken on the line 5—5 of Figure 3;

Figure 6 is a vertical sectional view taken on the line 6—6 of Figure 2, with the central portion of the Figure 2 showing omitted; and

Figure 7 is a fragmentary horizontal sectional view taken on the line 7—7 of Figure 3.

The numeral 10 designates the base of a baling press structure which is provided with tie rods 11 at each corner of one end thereof and a vertically extending tie rod 12 which is centrally positioned at the other end of the base. The tie rods 11 and 12 support the head 13 of the press. Cylinders 14 are mounted in the base 10 and rams 15 slidably therein support the movable platen 16 of the press at their upper ends. The fixed platen 17 of the press is supported by the head 13 in alignment with the movable platen 16. The baling chambers 18 of the press are supported upon a sleeve 19 which is rotatably mounted upon the tie rod 12, the chambers being diametrically oppositely positioned on the sleeve. 45 Roller bearings 20 are positioned about the tie rod 12 and on the base 10 to support the turning movement of the sleeve 19 and the baling chambers 18 carried thereby. By this arrangement, the baling chambers 18 may be rotated on the tie 50 rod 12 so that one of the baling chambers will be positioned in alignment with the movable platen 16 and the fixed platen 17, the other baling chamber 18 then resting upon a horizontally journaled roller 21 supported upon the base 10.

Each baling chamber 18 comprises a lower baling chamber 22 and an upper baling chamber 23. The walls of the upper and lower baling chambers are formed of vertically arranged channel beams 24 and 24, respectively in the usual man-

ner, the beams 24 forming the lower baling chamber 22 being fixed upon horizontally extending angle bars rigidly secured to brackets 25 upon the sleeve 19, angle bars 26 and 27 being positioned 5 adjacent the upper and lower ends, respectively, of the channel beams 24 of the lower baling chamber 22. An additional bracing structure for the channel beams 24 of the lower baling chamber 22 is provided by means of horizontally extending angle bars 27' positioned intermediate 10 the length of the channel beams 24. The bracing structure 27 also supports a press floor 28 about the baling chambers 18 and beneath the upper end of the lower chamber 22.

15 The baling chambers 18 are identical in construction and but one of them will therefore be described throughout the present specification.

Each of the upper baling chambers 23, which particularly comprise the subject of the present invention, includes side doors 29, an inner end door 30 and an outer end door 31, each of which is formed of relatively short vertically extending 20 channel beams 24'. The channel members 24' of the side doors 29 are riveted to upper and lower cross bars 35 and 36, respectively. The cross bars 35 are provided at their inner ends with horizontally arranged cylinders or sockets 37 and the lower cross bars 36 are provided at 25 their inner ends with similar elements 38. At the outer ends of the cross bars 35 and 36 are 30 similar cylinders or sockets 37' and 38', respectively. As is best shown in Figures 5, 6, and 7, the upper sockets 37 are longitudinally slotted at 39 on their lower surfaces and the lower sockets 38 are slotted at 40 on their upper surfaces. A vertically 35 extending hinge shaft 41 extends into the sockets through the slots 39 and 40, shaft 41 being journaled in flanges 49' formed integral with the sleeve 19. The ends of the shafts 41 within the sockets 37 and 38 have bifurcated 40 members 42 fitted thereon, the legs 43 of members 42 being provided with vertically extending bores 44 into which the ends of the shaft extend.

45 Integral stub shafts 45 project horizontally from the bifurcated members 42 and through apertures 46 in the outer ends of the cylindrical or socket members 37 and 38. The extreme ends 47 of the stub shafts 45 are reduced in diameter to form a shoulder 48 and reduced portion 47 is threaded to receive a nut. A fixed cam member 49 is fitted on the stub shafts 45 between the nut and the shoulder 48, the cam member 49 also being locked to the reduced portion 47 to prevent its rotation with respect to the stub shafts. Between 50 the fixed cams 49 and the outer surfaces of the socket members 37, there is mounted a movable cam member 50 provided with a laterally extending cam arm 51.

55 Referring to Figure 2, 5, and 7, it will be observed that the arms 51 of the movable cam members 50 of the upper and lower socket members 37 and 38 at the inner ends of the side doors 29 are connected by a link 52 so that the movable cam members 50 may be operated together. An outwardly projecting pin 53 is formed upon the outer surface of the link 52 and the lower end of a connecting rod 54 is pivotally mounted upon the pin 53 by means of a cotter pin or the like. The upper end of the connecting rod 54 is pivotally connected to the outer end of a crank 55 by a laterally projecting pin 56. The crank 55 is fixed to the end of a shaft 57 which is journaled in lugs 58 spaced upon the upper cross bars 35 of the side doors. The outer end of the shaft 57 has a cam operating lever 59 fixed thereto and

5 a connecting rod 60 is pivotally secured adjacent the inner end of the operating lever 59 by a pin 61. The lower end of the connecting rod 60 is pivoted to a link 62 which joins the cam levers 51' movable upon the upper and lower sockets 37' 5 and 38', respectively, at the outer ends of the side doors 29.

As is best shown in Figures 2 and 6, the sockets 37' and 38' at the outer ends of the side doors 29 are also provided with bifurcated members 42 and 10 fixed cams 49 similar to those already described. However, the shafts 63 and 64 which extend between the outer socket members 37' and 38' and through the bores 44 of the bifurcated members 42 therein on the opposite side doors 29 serve 15 as the axis of a latching member 65 and as a keeper therefor, respectively. As is shown in Figures 2, 4 and 6, upper and lower latch members 65 are mounted on the shaft 63 between the legs 43 of the bifurcated members 42 and the free 20 ends of the latch members 65 are adapted to engage the portions of the shaft 64 between the legs 43 of the bifurcated members 42 in which the shaft 64 is mounted, the cylinders 37' and 38' having slots 65' at their outer sides to permit 25 swinging of the latches and their engagement with the keepers 64. It will be understood from the above that the side doors 29 are held in closed position by means of the latch members 65 at their outer ends and that, when the latch 30 members are released, the doors may be swung outwardly upon their hinge shafts 41 to the position B shown at the extreme right hand end of Figures 2 and 3.

The inner end doors 30 of each of the upper 35 baling chambers 23 has the channel beams 24' thereof riveted to upper and lower cross bars 66 and 67, respectively. Cross bars 66 and 67 are provided with ears 68 (Figures 2 and 3) at each of the ends thereof, which ears are provided with 40 longitudinal slots 69. Upwardly projecting pins 70 fitted upon the upper inner socket members 37 of the side doors 29 project through the slots 69 in the upper cross bar 66 and downwardly projecting pins 71 fixed to the lower inner socket 45 members 38 project through slot 69 of the lower cross bar 67. It will be noted from the Figure 2 showings of two positions A and B, respectively, of the inner end and side doors, that when the baling chamber is in closed position A, the pins 50 70 and 71 will be at the inner ends of the slots 69 but that outer swinging movement of the end doors 29 to open position B will move the pins to the outer ends of the slots and will likewise move the inner end door 30 from the dotted line position 30' and toward the tie rod 12 so as to expand the baling chamber.

The outer end door 31 of each upper baling chamber has the channel members 24' thereof riveted to upper and lower cross members 72 and 60 73, respectively. Ears 73' are formed at the ends of the upper and lower cross members 72 and 73, which ears are positioned behind pins 70' and 71' which project upwardly and downwardly, respectively, from the socket members 37' and 38' 65 at the outer ends of the side doors 29 when the baling chamber is in the closed position A shown in both Figures 2 and 3. The outer end door 31 is somewhat longer or higher than the remaining doors of the upper baling chamber 23 and preferably extends down to a point beneath the baling floor 28. As is best shown in Figure 6, the lower end of the outer end door 31 is provided with an angled cross bar 74 which projects beneath cross rod 75 extending between the intermediate side 75

bars 21' which reinforce the lower baling chamber 22. The cross bar 74 and the cross rod 75 thus cooperate to form a hinged support for the outer end door 31. Outward swinging movement 5 of the outer end door 31 is limited by the bar 76 connecting the outer ends of the upper supporting angled bars 26 of the lower baling chamber.

In the operation of the baling press, with the side doors 29 and inner end door 30 in open position B shown at the extreme right hand end of Figure 2 and with the outer end door 31 in the dotted line position of Figure 6, to close the upper baling chamber 23, the upper end door 31 is swung inwardly on its hinge 74, 75 and the side doors 15 29 are swung inwardly on the hinge shafts 41 so that the pins 70' and 71' at the outer ends of the side doors will engage behind the ear 73' on the outer end door 31. The movement of the side doors 29 to this position will, through the movement of the pins 70 and 71 at the inner ends of the side doors 32 in the slots 69 in the inner end doors 30, move the doors 30 from the full line showing of position B to the dotted line showing 20 30' of position B, or, in other words, to a position 25 corresponding to position A of Figure 2. At this time, the surfaces 49' and 50' of the cams 49 and 50 will be in the interfitting relation shown in position B of Figure 2. When the doors have been moved to the position just described, the latch 30 levers 65 are swung inwardly against the outer end door 31 and into such a position that their latch ends may engage the latch rod or keeper 64. The cam operating levers 59 are then swung 35 downwardly to rotate the shaft 57, which movement will be transmitted to the cam levers 51 through the connecting rods 54 and 60 and the links 52 and 62, causing the movable cams 50 to move out of interfitting engagement with fixed cams 49 and to assume the position with respect 40 to the fixed cams 49 as shown in position A of Figure 2. This movement of the cams 50 with respect to the fixed cams 49 will cause the cylinders 37, 38, 37' and 38', and hence the side doors 29, to be moved inwardly upon the bifurcated 45 members 42 in a rectilinear direction with respect to the pivot shafts 41. The movement of the cams at the outer ends of the side doors 29 will likewise cause the rods 63 and 64 to move outwardly or apart with respect to each other, there- 50 by tightening the latch 65 upon the rod or keeper 64 and locking the baling chamber as shown in position A of Figure 2. The press may then be operated to compress the material into the upper baling chamber 23.

Upon the completion of the compressing operation, the cam operating levers 59 are raised, causing all of the cams 50 to be rotated with respect to the fixed cams 49 so that the surfaces 49' and 50' of the cams will interfit. This will 60 permit the inner ends of the side doors 29 to move outwardly, the socket members 37 and 38 at the inner ends of the doors sliding upon the bifurcated members 42 and away from the hinge shafts 41. At the outer ends of the side doors 29, 65 the interfitting of the cam members 49 and 50, resulting from the rotation of the cam arms 51' will permit the bifurcated members 42 and the sockets 37' and 38' to move with respect to each other, causing the rod 63 and latch 65 to move 70 slightly toward keeper rod 64 and also permitting that end of the doors 29 to move outwardly. The movement of the latch 65 and keeper 64 toward each other will permit the latch levers 65 to be readily disengaged from the keeper rod 64. The 75 side doors 29 may then be swung open sufficient-

ly to release the pins 70' and 71' at the outer ends thereof from behind the ears 73' on the outer end door 31 so that the latter door may be dropped back against the cross bar 76. Continuation of the outward swinging movement of the side doors 32 will, through the cooperation of the pins 70 and 71 at the inner ends of the side doors 29 with the slots 69 upon the inner end door 30, cause the inner end door 30 to be moved toward the sleeve 19 or from a position corresponding to the 10 dotted line 30' of position B of Figure 2 to the full line showing of position B of Figure 2.

It will be understood that the terms "side doors" and "end doors" used in the claims, as well as the other terms appearing in the claims, are 15 used for the purpose of description and not of limitation.

I claim:—

1. The combination in a baling press, of doors pivotally mounted and having rectilinear move- 20 ment with respect to their pivots, cooperating locking elements at the free ends of the respective doors and means to move said locking elements rectilinearly with respect to each other and to move said doors rectilinearly with re- 25 spect to their pivots.

2. The combination in a baling press, of a support, side doors and end doors, pivotally mounted members carried by said support, said side doors being mounted upon said members to 30 have rectilinear movement with respect thereto, cooperating locking means for said side doors respectively mounted on said doors at the free ends thereof, and means to effect the rectilinear movement of said doors with respect to said members 35 and to operate said locking means.

3. The combination in a baling press, of side doors and end doors, a support, vertical pivot shafts carried by said support, said pivot shafts having horizontal extensions thereon upon which 40 said side doors are mounted, and means to move said side doors upon said horizontal extensions to lock them in bale forming position, a keeper carried at the free end of one of said side doors, a latching member carried at the free end of the 45 other of said side doors, and means to move said latch member and keeper with respect to each other.

4. The combination in a baling press, of side doors and end doors, a support, said side doors 50 being pivotally mounted upon said support at one end thereof, a keeper at the free end of one of said side doors, a latching member to engage said keeper carried at the free end of the other of said side doors, and means to move said latch 55 member and keeper longitudinally with respect to each other.

5. The combination in a baling press, of side doors and end doors, a support, pivots for said side doors carried by said support and including 60 horizontal extensions upon which said side doors are mounted, a keeper at the free end of one of said side doors, a latching member at the free end of the other of said side doors, and means to move said side doors rectilinearly upon said horizontal 65 extensions and to move said latch member and keeper with respect to each other comprising simultaneously operated cooperating cam members.

6. The combination in a baling press, of side 70 doors and end doors, a support, a pivot for said side doors carried by said support and including horizontal extensions upon which said side doors are mounted, a keeper at the free end of one of said side doors, a locking member at the free end 75

- of the other of said side doors, means to move said side doors relatively to said horizontal extensions and to move said latch member and keeper with respect to each other, one of said end doors being supported upon said side doors and operatively connected thereto so that swinging movement of said side doors will move said end door rectilinearly, a pivot for the other of said end doors carried by said support, said last named end door being held in locked position between the free ends of said side doors. 5
7. The combination in a baling press, of a support, members pivoted at each side of said support, doors carried by and rectilinearly movable on said members, rectilinearly movable elements at the free end of said doors, a keeper carried by one of said elements and a latch carried by the other of said elements, and means to move said doors rectilinearly upon said pivoted members and to move said elements rectilinearly with respect to said doors. 10
8. The combination in a baling press, of side doors pivoted on a vertical axis, and an end door pivoted on a horizontal axis, locking means comprising cooperating locking elements for said side doors, and means to move said locking elements relatively to each other when in locking position to permit them to be substantially released and the side doors opened, and holding means for said end door carried by said side doors and positioned thereon to hold said end door in closed position until the side doors are opened. 15
9. The combination in a baling press, of a member mounted pivotally at one end thereof, a door mounted upon said member and means to move the door axially of said member. 20
10. The combination in a baling press, of a pivotally mounted member, a door mounted upon said member and means to move the door rectilinearly with respect to said member. 25
11. The combination in a baling press, of a pivotally mounted member, a door mounted upon said member and means to move said door relatively to said member comprising cooperating cam members operatively connected to said door and said member. 30
12. The combination in a baling press, of a pivotally mounted member, a door mounted upon said member and means to move said door rectilinearly with respect to said member comprising cooperating cam members operatively connected to said door and said member. 35
13. The combination in a baling press of side doors and end doors, a support, vertical pivot shafts carried by said support, said pivot shafts having horizontal extensions thereon upon which said side doors are mounted, and means to move said side doors relatively to said horizontal extensions to lock them in bale forming position. 40
14. The combination in a baling press, of pairs of side doors and end doors, a support, pivots for one of said pairs of doors carried by said support and including horizontal extensions upon which the doors of said pair are mounted, a keeper at the free end of one of the pivoted doors, a latching member at the free end of the other pivoted door, and means to move said doors rectilinearly upon said horizontal extensions and to move said latching member and keeper with respect to each other. 45
15. The combination in a baling press, of side doors and end doors, a support, pivots for said side doors carried by said support and including horizontal extensions upon which said side doors are mounted, a keeper at the free end of one of 50
- said side doors, a latching member at the free end of the other of said side doors, and means to move said side doors rectilinearly upon said horizontal extensions and to move said latch member and keeper with respect to each other. 55
16. The combination in a baling press, of a support, a pair of side doors pivoted upon opposite sides of said support, an end door supported upon said side doors at the pivoted end of the latter, a pin and slot connection between said side doors and said end door to cause said end door to move rectilinearly when said side doors are turned upon their pivots. 60
17. The combination in a baling press, of side doors and end doors, a support, vertical pivot shafts carried by said support, said pivot shafts having horizontal extensions thereon upon which said side doors are mounted, and means to move said side doors rectilinearly upon said horizontal extensions to lock them in bale forming position, a keeper carried at the free end of one of said side doors, a latching member carried at the free end of the other of said side doors, and means to move said latch member and keeper with respect to each other. 65
18. The combination in a baling press, of side doors and end doors, a support, members vertically pivoted on said support and carrying said side doors, said side doors being mounted upon said members to have rectilinear movement with respect thereto, an end door carried by said side doors at their ends adjacent said members and connected to said side doors to move rectilinearly when said side doors are swung upon said vertically pivoted members, and operative connections between the free ends of said side doors and the other of said end doors to hold the latter door substantially in closed position during the rectilinear movement of said side doors. 70
19. The combination in a baling press, of oppositely disposed doors, locking means for said doors comprising a pivoted latch carried by one door and a keeper carried by the other door, said latch and said keeper being mounted for rectilinear movement with respect to said doors and each other. 75
20. The combination in a baling press, of oppositely disposed doors, locking means for said doors comprising a pivoted latch carried by one door and a keeper carried by the other door, said latch and said keeper being mounted for rectilinear movement with respect to said doors and each other, and means to move said latch and keeper toward each other when in engaged position. 80
21. The combination in a baling press, of doors pivotally mounted and having rectilinear movement with respect to their pivots, cooperating locking elements at the free ends of the doors and simultaneously operable means to move said locking elements rectilinearly with respect to each other and to move said doors rectilinearly with respect to their pivots. 85
22. The combination in a baling press, of a support, side doors and end doors, pivotally mounted members carried by said support, said side doors being mounted upon said members to have rectilinear movement with respect thereto, cooperating locking means for said side doors respectively mounted on said doors at the free ends thereof, and simultaneously operable means to effect the rectilinear movement of said doors with respect to said members and to operate said locking means. 90
